(57) **CLAIM**

The ornamental design for an earhook for earphone, as shown and described.

DESCRIPTION

FIG. 1 is a front, top, and left perspective view of an earhook for earphone, showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a rear, bottom, and right perspective view thereof;

FIG. 9 is a front, top, and left perspective view thereof in reduced scale, in which an earphone is installed to face a first direction in use; and,

FIG. 10 is a front, top, and left perspective view thereof in reduced scale, in which an earphone is installed to face a second direction opposite to the first direction in use.

The broken lines shown in FIGS. 9 and 10 depict environment and form no part of the claimed design.

1 Claim, 8 Drawing Sheets
